UNITED STATES PATENT OFFICE.

CHARLES J. SINN AND HENRY G. WELLS, OF CRISFIELD, MARYLAND.

CAN-CLOSURE.

1,312,587.

Specification of Letters Patent. Patented Aug. 12, 1919.

Application filed March 11, 1918. Serial No. 221,852.

To all whom it may concern:

Be it known that we, CHARLES J. SINN and HENRY G. WELLS, citizens of the United States, residing at Crisfield, in the county 5 of Somerset and State of Maryland, have invented certain new and useful Improvements in Can-Closures; and we do hereby declare the following to be a full, clear, and exact description of the invention, such as will enable others skilled in the art to which it 10 pertains to make and use the same.

This invention relates to can closures, and has for an object to provide a closure, embodying improved features of convenience, 15 reliability, and economy.

A further object of the invention is to provide a can closure, embodying a slip cover, having a tongue extending circumferentially in relation to the flange of the 20 cover, and produced by an L shaped slot, with an ear or loop struck up from the flange of the can body, positioned to receive the tongue of the cover member when the cover is slipped to position, and rotated upon the 25 can.

With these and other objects in view, the invention comprises certain novel features of construction, combinations and arrangements of parts, as will hereinafter be more 30 fully described and claimed.

In the drawing;

Figure 1 is a perspective view of the can with the cover lifted.

Fig. 2 is a vertical sectional view through 35 the struck up loop, and transversely through the tongue.

Like characters of reference designate corresponding parts, throughout the several views.

40 The improved can closure which forms the subject matter of this application, is adapted to be applied to almost any type of cylindrical cans, as indicated at 10, having a flange 11, and preferably although not necessarily, also a bead 12.

The cover member 13, is in general appearance of the usual and ordinary slip type, having a flange 14, which however, is pro-

vided with an L shaped slot 15, producing a tongue 16, having its major axis extending 50 circumferentially of the cover flange.

At an appropriate point in the body flange 11, a loop 17 is struck up by the producing slits 18, in substantial parallelism, extending also in parallelism with the axis of the can 55 body. The loop 17 is then forced outwardly from the axis of the can, so that the opening of such loop, or the interval between the loop member 17 and the surface of the body flange, is in the path of movement of the 60 tongue 16, as it is moved circumferentially.

In operation, the can cover is placed upon the body flange in substantially the usual and ordinary manner, and is then rotated manually in the direction opposite to that 65 indicated by the arrows, upon the body flange and the cover flange, until the tongue 16 has entered the loop, and has been moved to its limit of circumferential movement. In this position it is obvious that the cover is 70 firmly locked against displacement. To remove the cover, the cover is rotated in the direction indicated by the arrows, until the tongue 16 has been released from engagement with the loop 17, when the cover may 75 be removed as an ordinary slip cover.

While in the drawing, two of the locking members are indicated, it is obvious that any desired number may be substituted therefor.

We claim:

The combination with a can body having a cover-receiving flange, of a loop produced by spaced slits, said loop being forced outwardly beyond the circumferential limits of the flange, a cover having a flange proportioned to slip over the flange of the can body, and to be manually rotated relatively thereto, and a tongue formed in said cover flange by an L shaped slot, said tongue being positioned and proportioned to slip through the 85 loop when the cover is rotated.

In testimony whereof we affix our signatures.

CHARLES J. SINN.
HENRY G. WELLS.
